Application February 18, 1943, Serial No. 476,368

9 Claims. (Cl. 179—100.2)

1

My invention relates to sound recording and reproducing systems and more particularly to magnetic recorders and reproducers known as telephones in which, as is well known, the signals are recorded by varying the magnetic condition of a moving magnetic member and are reproduced by causing such a magnetized member to vary the induction in a suitable translating device.

The object of my invention is to provide a novel method and apparatus of this kind and in general to improve the operation of such a recording and reproducing system.

My invention relates particularly to a magnetic recorder and reproducer adapted to record longitudinally on extremely thin wire. The advantages of the longitudinal type of magnetic recording on thin wire are well known and are primarily due to the fact that the recorded magnetic impulses are impressed upon the wire in a manner which is symmetrical with respect to the longitudinal axis of the wire and consequently precautions against twisting and turning of the wire are not required either for recording or reproducing.

While magnetic recorders and reproducers are old and well known, they have never been used commercially to an extent comparable to the use of phonographs or film recording. There are a number of reasons for this, the more important of which are probably due to the fact that satisfactory quality of reproduction and satisfactory length of duration of the recorded program was possible only with quite voluminous apparatus using a large amount of magnetic wire and tape which occupied considerable storage space compared to other methods of recording such as film or phonograph disc.

In accordance with the general features of this invention certain engineering requirements are necessary regarding the size and general arrangement of the elements used with particular reference to the size of the wire. It is required that the wire be sufficiently large to provide at each instant a magnetic moment that is capable of overriding the spurious magnetic moments generated by a stray extraneous field and that is sufficiently large so that its statistical fluctuations are small in comparison. It has been demonstrated that these requirements can be met by extremely thin wire of the order of $1/1000$ of an inch thick and it has been demonstrated that the use of such wire offers numerous important advantages, the main one of which is compactness of the storing mechanism and consequent adaptability of this system to the recording of long

2

continuous messages. It has been demonstrated that the limit to the thinness of the wire used is not caused by electric or magnetic considerations, but is due to the mechanical difficulties involved in the handling and threading of the extremely thin wire.

An important feature of my invention consists in providing a removable and compact cartridge type container which will include the magnetic wire in combination with a winding mechanism and the element for impressing a magnetic field upon the wire. It will become apparent from the further description that the full advantages of the longitudinal type of magnetic recording on wire of small diameter cannot be realized without the use of the proposed cartridge type container. I propose to use wire of extremely small diameter and to provide the container that is dust tight and permanently enclosed. The wire contained in it shall be used over and over again without removing the wire from the container and without ever rethreading the wire through the recording head and the erasing head. The advantages of this arrangement are that an extremely long message can be recorded and stored within a single magazine having relatively small dimensions. For example, in a magazine of 3" by 7" by 1" dimensions by using the principle of my invention it is possible to record a message lasting one-half hour. This is more economical of space than any prior arrangement of magnetic recording and actually compares very favorably with the most economical recording means, such as recording on film or recording on a phonograph disc.

Another object of my invention is to provide means for impressing a concentrated magnetic field on the wire. Such a concentration of magnetic field in the small space immediately surrounding the wire is accomplished by means of an element hereinafter referred to as the recording head. The recording head consists of a high permeability magnetic core that provides an entirely closed magnetic circuit with the exception of a small air gap. A winding is provided around the magnetic core and the said winding receives the signal currents and produces in the magnetic core a magnetic flux varying in accordance with the message to be recorded. Furthermore, the core is provided with a small hole parallel to the direction of magnetic flux and crossing the air gap. The magnetic wire on which it is desired to record a message passes through this hole in a manner such that the wire is entirely shielded from the magnetic field generated by the core except at the point where the wire traverses the

air gap. The magnetic circuit is arranged so as to consist entirely of high permeability material except for a single air gap mentioned above.

Further objects of my invention will become apparent in the description of my invention and in the enclosed drawings. In the drawings:

Fig. 2 illustrates the general arrangement of a speech recording and reproducing mechanism and shows various elements thereof.

Fig. 1 shows an exterior view of the speech recording and reproducing device.

Fig. 3 shows an exterior view of the removable magazine which constitutes one of the elements of the device illustrated in Fig. 1.

Fig. 4 shows a cutaway rear view of the removable magazine showing the working parts.

Fig. 4A shows a cross section of the recording head.

Fig. 4B shows a view of the flux concentrating arrangements.

Fig. 4C shows a cross section of the erasing coil.

Fig. 5 shows the general wiring diagram of the magnetic recorder.

Referring now more particularly to the drawings, the arrangement illustrated in Fig. 4 designated by the numeral 10 shall be designated hereafter as "removable magazine." The removable magazine contains drums 11 and 12 which are driven by shafts 13 and 14 and are provided with disengageable clutch members 15 and 16. These clutch members make it possible to engage or disengage the shafts 13 and 14 with the shafts 17 and 18 and clutch members 15a and 16a respectively shown on the master station illustrated on Fig. 2.

Referring now to Fig. 2, shafts 17 and 18 are provided with pulleys 9 and 20 which are connected by a belt 22 and are driven from the drive pulley 19 which in turn is driven by the motor 23, the motor 23 being preferably of the synchronous type and being arranged through the mechanism just described to drive the drums 11 and 12 shown on Fig. 4. The mechanism just described consisting of a synchronous motor 23, and the drive pulley and belts, and also certain amplifying and transducing mechanisms that shall be described later, are all contained in a housing 24, and constitute a master unit adapted to receive the interchangeable cartridge 10. The interchangeable cartridge 10 and the master unit 25 are provided with suitable plugs which are arranged to make the proper electrical connection required between the master unit 25 shown on Fig. 2 and the magazine 10 shown on Fig. 4. The plugs are designated by the numerals 101 and 102 on both the drawings of Fig. 2 and Fig. 4. In addition to providing the necessary electrical connection these plugs are arranged to couple the two units with the required mechanical rigidity so that when in place the magazine 10 becomes an integral part of the whole mechanism.

Fig. 1 illustrates a general exterior view of the master unit with the removable magazine designated by the numeral 10 in place and Fig. 3 represents a view of the removable magazine 10 with the plugs 101 and 102 and clutch members 15 and 16 projecting from the surface.

With reference now to Fig. 4, numerals 11 and 12 designate the drums which are used both to drive the wire and to store the wire. The wire itself is designated by the numeral 32 and is arranged to pass from the storage drum 12 through the erasing mechanism 33 and through the recording head 35 and onto the storage and drive drum 11. The erasing device 33 consists essen-

tially of a coil of wire wound on an axis coincident with the axis of a small cylindrical hole 36 through which the wire passes. The winding 31 is wound on a bobbin 38 which is preferably made of Bakelite or wood or some other non-magnetic material. The recording head 35 consists of a high permeability core 40 which is made of a series of thin laminations 41 insulated one from the other. The winding 42 is wound around an axis that coincides with the position occupied by the wire 32 as it passes through the hole 43 provided in the high permeability core 40. The single air gap in the magnetic circuit is shown in cross section in Fig. 4A and within that air gap is placed a flux concentrating arrangement which is also illustrated in this figure. It is apparent that for satisfactory performance the length of the air gap bears relationship to the speed of the wire and to the highest frequency that it is desired to record. With these considerations in mind the length of the air gap should be of the order of the wave length of the highest frequency that it is desired to record. For example, if the highest frequency to be recorded is 3000 cycles and the speed of the wire is 3 feet per second then the length of the air gap should be of the order of $1/100$ of an inch.

Referring now more particularly to Figure 4A, as mentioned previously, the recording head 35 is provided with a single air gap. In order to concentrate the flux as much as possible into the region occupied by the wire, a special flux concentrating arrangement is used and designated by the numeral 44. With further reference to Fig. 4A, numeral 40 designates the high permeability material which constitutes the magnetic circuit, 42 designates the winding and 43 the hole through which the wire passes, 63 designates two tubular pole pieces made of high permeability material which are designated to concentrate the flux into the region occupied by the wire. Numeral 64 designates a brass (or Bakelite or other non-magnetic material) spacing arrangement which serves to separate the pole pieces 63 one from the other and provide an accurate alignment of the magnetic circuit.

Fig. 4B illustrates the flux concentrator separately. Numeral 63 designates the high permeability tubular pole pieces and numeral 64 designates the brass or Bakelite block that serves to align the pole piece accurately. Numeral 43 indicates the hole through which the wire is passed.

Fig. 4C illustrates a cross section through the erasing coil which has been designated as 33 on Fig. 4 and numeral 38 designates the Bakelite or other non-magnetic material bobbin and numeral 37 indicates the winding which is wound around the axis 75. 36 indicates the hole through which the wire passes.

Fig. 5 illustrates the electrical wiring diagram of the arrangement illustrated on the previous figures. An important part of the arrangement is the provision of the plugs which are arranged to connect and disconnect the apparatus housed within the magazine from the apparatus housed within the master unit, numeral 101 indicates the plugs which are arranged to connect and disconnect the recording head circuit and the apparatus located within the master unit and numeral 102 designates the plugs used to connect and disconnect the erasing coil with the apparatus located within the master unit. Another important part of the circuit is the switch arrangement which consists of the double pole switches 103, 104, 105, 106 and 107 all of these switches

are arranged to be controlled by a single lever so that when the lever is in the "record" position the switches 103 to 107 are all in the "up" position as indicated by the solid arrows in Fig. 5. When the switch is placed into the "reproduce" position all the switches are in the "down" position which corresponds to the dotted lines shown on Fig. 5. Assume now that the switches are in the "up" position indicated by the solid arrows and with further reference to Fig. 5 the operation is as follows:

Sound waves impinge upon the electrodynamic loud speaker, 108. This loud speaker is arranged to operate satisfactorily either as a loud speaker or as a microphone. When it operates as a microphone the sound waves impinge upon the diaphragm and cause motions in the electrodynamic transducing mechanism which generate electrical currents that are representative of the sound waves. Usually, when a loud speaker is operated in this manner, i. e., as a microphone, its frequency characteristic is unsatisfactory and requires equalization in order to improve the quality of the reproduced sound. Therefore on Fig. 5 the speech currents generated by the loud speaker 108 are impressed through the switch 103 on an equalizer 109 which serves to improve the quality of reproduction in a manner that is well known in the art. After passing through the equalizer the speech currents are impressed through the switch 104 on to the amplifier 110. The output of the amplifier is impressed through the switches 105 and 106 and the plug 101 on to the recording head 35. In the recording head alternating magnetic fields are impressed upon the wire 32 which are a reasonably exact facsimile of the sound waves that originally impinged upon the diaphragm of the loud speaker 108. Before the wire 32 passes through the recording head 35 it is demagnetized by passing through the demagnetizing coil 33. This demagnetizing coil is energized with a high frequency alternating current which is generated by the oscillator 114 and which is impressed on the demagnetizing coil through the switch 107 and the plugs 102. In the arrangement shown (switches in the "up" position) the wire 32 therefore is demagnetized first in the coil 33 and then passes through the recording head 35 in which alternate magnetic field is generated which represents the speech.

Assume now that the switch is in the down position, i. e., the switches 103, 104, 105, 106, 107 occupy the position shown by the dotted lines on Fig. 5. This corresponds to the "reproduce" condition and the operation of the circuit is as follows:

The oscillator 114 is now disconnected from the erasing coil 33 and the erasing coil therefore is not energized and the wire in passing therethrough retains whatever magnetism that existed in it. The wire now passes through the recording head 35 which responds to the magnetic field generated by the wire and produces a voltage across the winding of the recording head which is approximately proportional to the rate of change of the magnetic flux. This voltage is impressed across the plug 101 and through the switch 106 is impressed across the terminals of the equalizer 120. This equalizer serves essentially as an "integrator" such an integrator has been previously described in U. S. Patent No. 2,099,536 and reference is made thereto. The purpose of this integrator is to produce a voltage at its output which is substantially proportional to the integral of the input and consequently which is

substantially proportional to the flux generated in the recording head 35 rather than to the rate of change of flux therein. The output of the equalizer 120 is impressed through the switch 104 onto the input of amplifier 110 and the output of the amplifier 110 is connected to the switch 105 and 103 onto the loud speaker 108 which is arranged to transduce the electric current into audible sound. The operation of the circuit therefore is such that the loud speaker 108 generates a sound which is substantially a facsimile of the magnetic flux generated in the recording head 35.

I claim:

1. In a combined recorder-reproducer a removable magazine, said magazine comprising record spools with a windable magnetizable element and recording-reproducing head mounted in operative relation to said element, a housing adapted to receive said magazine and comprising a driving means engageable into said spools, an electromechanical transducer, two electrical networks differing in characteristics one from the other and having their output terminals connectable to said recording-reproducing head, and an electrical switch system for selectively inserting one of said networks between said transducer and said recording-reproducing head for recording signals derived from said transducer upon said windable element and for selectively inserting the other of said networks between said transducer and said recording-reproducing head for reproducing signals from said windable element into said transducer.

2. In a combined recorder-reproducer a removable magazine, said magazine comprising record spools with a windable magnetizable element, a recording-reproducing head and an erasing head mounted in operative relation to said element, a housing adapted to receive said magazine and comprising a driving means engageable into said spools, an electromechanical transducer, two electrical networks differing in characteristics one from the other having their input terminals connectable to said transducer and having their output terminals connectable to said recording-reproducing head, a source of voltage connectable to said erasing head, and an electric switch system for connecting said source of voltage to said erasing head and simultaneously inserting one of said networks between said transducer and said recording-reproducing head, and for selectively inserting the other of said networks between said transducer and said recording-reproducing head and simultaneously disconnecting said source of voltage from said erasing head.

3. A magnetic reproducing device comprising a removable magazine and a housing adapted to receive the magazine, said magazine comprising a drum rotatably mounted on a shaft provided with a clutch member, a magnetic windable element wound upon said drum and adapted to be moved by the rotation of the shaft, a reproducing electromagnet and an erasing electromagnet mounted in operative relation to said element, said reproducing electromagnet and said erasing electromagnet being respectively connected to electrical terminals conveniently fastened to the walls of the magazine; said housing comprising a motor, a shaft driven by said motor and provided with a clutch member, an electromechanical transducer for translating sound waves into electrical voltages, electrical plugs conveniently located within said housing and connectable to the said transducer, a source of current, electrical plugs conveniently located within said housing

and connectable to said source of current, a switch for selectively connecting either said transducer or said source of current to their respective plugs, the removable magazine and the housing being adapted to become engaged and disengaged one from the other and having their clutch members and electrical plugs arranged so that while the magazine is engaged with the housing the said clutch members are engaged thus permitting the motor of the housing to drive the shaft of the magazine and to move the windable element, and the electrical plugs connectable to the said transducer are in contact with electrical terminals connected to said recording electromagnet while the electrical plugs connectable to the output of said source are in contact with electrical terminals connected to said erasing electromagnet, thus permitting for one position of said switch the output of said reproducing electromagnet to be transmitted to said transducer and to produce sound waves in response to the magnitude impressions picked up by said reproducing electromagnet, and for the other position of said switch the output of said source to be transmitted to the erasing electromagnet and to produce upon the moving magnetic element magnetic fields causing the erasure of magnetic impressions.

4. A magnetic recording and reproducing device comprising a removable magazine and a housing adapted to receive the magazine, said magazine comprising a drum rotatably mounted on a shaft provided with a clutch member, a magnetic wire wound upon said drum and adapted to be moved by the rotation of the shaft, a recording-reproducing electromagnet and an erasing electromagnet mounted in operative relation to said wire, said recording-reproducing electromagnet and said erasing electromagnet being respectively connected to electrical terminals conveniently fastened to the walls of the magazine; said housing comprising a motor, a shaft driven by said motor and provided with a clutch member, an electromechanical transducer for translating sound waves into electrical voltages or vice-versa, two electrical networks differing in characteristics one from the other and having their input terminals connectable to said transducer, electrical plugs conveniently located within said housing and connectable to the output terminals of said networks, a source of current, a switching mechanism for selectively connecting said transducer to the input terminals of one of said networks and the output terminals of said network to the corresponding plugs and simultaneously connecting said source of current to the corresponding plugs, or for selectively connecting said transducer to the input terminals of said other network and the output terminals of said other network to the corresponding plugs and simultaneously disconnecting the source of current from the corresponding plugs, the removable magazine and the housing being adapted to become engaged and disengaged one from the other and having their clutch members and electrical plugs arranged so that while the magazine is engaged with the housing the said clutch members are engaged thus permitting the motor of the housing to drive the shaft and to move said magnetic wire, and the electrical plugs connectable to the output terminals of said networks are in contact with electrical terminals connected to said recording-reproducing electromagnet while the electrical plugs connectable to said source are in contact

with electrical terminals connected to said erasing electromagnet.

5. In a telegraphone, a reproducing head comprising an electric coil, a single magnetic member provided with two extremities and interlinking with said coil in a manner as to have the two extremities in the immediate neighborhood one with respect to the other and separated by a short path of a high reluctance medium whereby the current traversing said coil produces flux interlinking with said coil and following a path the major portion of which is contained entirely within said magnetic member and a small portion of said path traversing said high reluctance medium between said two extremities, said magnetic member having in a portion thereof elongated openings in the direction of a portion of said magnetic path and through which the wire to be magnetized is passed in a direction substantially parallel to the lines of magnetic flux, and two tubular elements imbedded in said openings and surrounding said wire, said tubular elements having relatively high magnetic permeability and being separated one from the other by a relatively small distance within said high reluctance medium whereby the magnetic flux traversing said high reluctance medium tends to be concentrated within the space separating said tubular elements, and a microphone connected to said coil for translating sound waves into electrical currents thereby producing a magnetic field interlinking with said coil and traversing said magnetic member and the said high reluctance path.

6. A magnetic recorder for magnetizing a wire to provide a sound record comprising a solid member having a relatively low magnetic reluctance and symmetrical with respect to an axis, said member having an elongated opening of small cross section longitudinally aligned along the direction of said axis through which a wire to be magnetized is passed; a tubular element imbedded in said opening and surrounding said wire, said tubular element having a relatively low magnetic reluctance, an electric coil imbedded in said member and surrounding said axis, a microphone connected to said coil for translating sound waves into electrical currents thereby producing a magnetic field interlinking with said coil and having a portion thereof aligned in the direction of said axis, said magnetic member containing a portion of space having a relatively high magnetic reluctance and separating two portions of said tubular element thereby localizing the maximum strength of the magnetic flux in said space separating said two portions.

7. A magnetic recorder for magnetizing a wire to provide a sound record comprising two elongated magnetic members disposed longitudinally in such a manner that the axis of one of said members forms the extension of the axis of the other member in a longitudinal direction, said members having their adjoining extremities separated by a high reluctance gap and having elongated longitudinal openings aligned with said axis and completely surrounded by the material of said members whereby a wire to be magnetized can be moved longitudinally through said openings, a continuous magnetic core member connecting the non-adjoining extremities of said members to provide a continuous and uninterrupted low reluctance magnetic path, a coil mounted in an operative relationship to said members for producing a flux traversing said members in the direction of said axis and an

electromechanical transducer connected to said coil for translating sound waves into an electric current.

8. A magnetic recorder for magnetizing a wire to provide a sound record comprising two elongated low reluctance members disposed longitudinally in such a manner that the axis of one of said members forms the extension of the axis of the other member in a longitudinal direction, said members having their adjoining extremities separated by a high reluctance gap and having elongated longitudinal openings aligned with said axis whereby a wire to be magnetized can be moved longitudinally through said openings, tubular elements imbedded in said openings and surrounding said wire, a magnetic core member connecting the non-adjoining extremities of said members to provide a low reluctance magnetic path, a coil mounted in an operative relationship to said members for producing a flux traversing said members in the direction of said axis, and an electromechanical transducer connected to said coil for translating sound waves into an electric current.

9. In a magnetic reproducer for reproducing sound from a magnetized wire, comprising two longitudinal magnetic core members aligned along the same axis and positioned with a pole piece of one and a pole piece of the other displaced one with respect to the other along the said axis whereby the planes of said pole pieces are perpendicular to said axis, said core members being provided with elongated openings along said axis through which the magnetized wire is passed with the longitudinal dimension

15
